and horizontal and vertical or of cylindrical curvature to be situated within a flue or chimney tube, and which is capable of being held in a closed position by a valve plate which is hinged to the valve body and which is capable of being held in an open position by a counterweight.

It is an object of the present invention to provide a valve assembly which is capable of being held in a closed position by a valve plate which is hinged to the valve body and which is capable of being held in an open position by a counterweight.

UNITED STATES PATENT OFFICE

1,988,539

DOUBLE ACTING AUTOMATIC DRAFT CONTROL DEVICE

Marvin Wayne Bowersox, Salina, Kans.

Application October 28, 1933, Serial No. 695,713

3 Claims. (Cl. 236—45)

This invention relates to an automatic operable draft control device for use in connection with gas and oil burning furnaces and it has more particular reference to a double acting draft regulating valve of the swingable shutter plate type.

As the preceding statement of the invention implies I have evolved and produced a novel draft control unit comprising a casing attachable to a flue pipe wherein said casing is equipped with an especially constructed valve arrangement of a counterbalanced type including an hingedly mounted valve plate normally positioned in the casing and swingable inwardly to facilitate the introduction of air into the flue, and bodily swingable outwardly beyond the end of the casing to take care of abnormal explosive downdraft, whereby to promote uniform operation of the burner so far as the draft supply is concerned.

Needless to say, I am aware of the fact that the prior art to which the invention relates discloses similar double acting valves designed to accomplish somewhat the same fundamental results. My primary aim, therefore, is to generally improve upon these known prior patented structures by providing a different and unique valve assembly and mounting calculated to promote more effective regulation and positive action and to more effectively fulfill the requirement of a structure of this kind.

Other features and advantages of my invention will become more readily apparent from the following description and drawings.

In the drawings:—

Figure 1 is an end elevational view of the valve control device showing the valve plate or shutter as closed.

Figure 2 is a view taken approximately on the plane of the line 2—2 of Figure 1, with parts shown in phantom style to better portray and emphasize the principal improvement.

Figure 3 is a perspective view of the valve plate. Figures 4, 5 and 6 are detail perspective views. Referring first to Figure 2 it will be observed that the numeral 7 designates a draft pipe the lower end 8 of which is suitably attached to the furnace flue connection (not shown) and the upper end 9 of which is appropriately connected with the chimney or flue (not shown). The numeral 10 merely designates an attaching nipple to which the improved unit, designated as a whole by the numeral 11 is attached. The unit may be of any appropriate cross-sectional shape but it preferably comprises a sheet metal casing 12 whose inner end 13 is fashioned for connection to the cylindrical nipple 10 and whose outer end

portion is of square or rectangular form to accommodate the valve assembly.

The valve assembly is characterized primarily by a valve plate or shutter 14, this being pivotally or hingedly connected as at 15 to a hinged bracket 16 carried by a pendulous-like bar or arm 17. The bar 17 is in the form of an elongated flat strip of metal which is hingedly attached intermediate its ends as indicated at 18 to the lower portion or bottom of the casing shown in Figure 2. The extreme upper end thereof 19 constitutes a stop and is engageable in the bead 20. The lower or depending end portion 21 has a slidably adjusting weight 22 held in place by a set screw 23. This permits the pendulous-action of the bar to be regulated and controlled according to predetermined conditions. Thus it will be seen that I provide a pendulous-like bar 17 hingedly attached between its ends as at 18 to the outer end of the casing 12 with its upper end 19 engaging the bead 20 and the lower end 21 depending and carrying an adjustable weight 22, said bar serving to accommodate a hinged bracket 16 on which swingably mounted or pivotally attached a shutter plate 14 is suspended.

The plate itself is adjustable in action and is, therefore, provided with a U-shaped mounting fixture 24 designed to accommodate a slidably counterweight 25 held in said position by a screw 26. Consequently the two parts 17 and 14 are independently adjustable as to sensitivity of action.

Under normal draft conditions the valve unit or assembly occupies the full line position shown in Figure 2. That is, the pendulous arm or bar 17 is substantially perpendicular with its upper end 19 resting against the stop bead 20. Of course, the position of the valve plate 14 depends on the degree of suction developed in the flue 7. For example, when the valve plate 14 is closed it occupies the perpendicular position shown in Figure 1. When the suction is increased in the flue the valve plate 14 swings inwardly to admit air into the flue by way of the casing 12 and nipple 10. The action of this valve plate can be controlled by regulating the counterweight 25. Under abnormal draft conditions when the down draft becomes expansive in action, the overcharge of pressure is relieved or exhausted through the casing 12 under which condition the valve plate 14 swings down against the bar 17 causing the bar to swing outwardly to the dotted line position shown in Figure 2 against the action of the adjustable weight 22. Here again it is to be pointed out

that this exhaust relief action can be regulated more or less by the position of the weight 22.

A careful consideration of the foregoing description in conjunction with the illustrative drawings will enable the reader to obtain a clear understanding of the purpose, features and advantages, the explicit construction, and the invention as hereinafter claimed.

It is to be understood that minor changes in shape, size, relative proportions, and materials may be resorted to in practice without departing from the spirit of the invention or the scope of the invention as now claimed.

What is claimed is:—

15. 1. A device of the class described comprising a casing attachable to a flue, a bar hingedly attached intermediate its ends to the bottom of said casing, the upper portion of said bar spanning the open outer end of said casing with its upper extremity engageable with the top wall of the casing to limit the swinging movement of the bar in one direction, the lower end portion of said bar depending below the casing, a regulating weight adjustably mounted on said lower end portion, and a valve plate normally disposed within the limit of said casing and hingedly attached at its upper end to the corresponding end portion of said bar, said valve plate corresponding in shape and proportion to the casing and being provided on its inner side with a guide fixture, and an adjusting weight slidable on said guide fixture.
20. 3. The combination of a pipe having an opening therein, a bar having an intermediate part hingedly connected to the bottom part of the pipe adjacent the opening, an adjustable weight on the lower part of the bar, said weight normally holding the bar across the opening with its upper end contacting an upper portion of the pipe, a valve member for closing the opening and having its top part hingedly connected to the upper part of the bar, a weight supported from the valve member for vertical movement, and means for holding the weight in adjusted position.

MARVIN W. BOWERSOX.

1. A device of the class described comprising a casing attachable to a flue, a bar hingedly attached intermediate its ends to the bottom of said casing, the upper portion of said bar spanning the open outer end of said casing with its upper extremity engageable with the top wall of the casing to limit the swinging movement of the bar in one direction, the lower end portion of said bar depending below the casing, a regulating weight adjustably mounted on said lower end portion, and a valve plate normally disposed within the limit of said casing and hingedly attached at its upper end to the corresponding end portion of said bar.

2. A device of the class described comprising a casing attachable to a flue, a bar hingedly attached intermediate its ends to the bottom of said casing, the upper portion of said bar spanning the open outer end of said casing with its upper extremity engageable with the top wall of the casing to limit the swinging movement of the bar in one direction, the lower end portion of said bar depending below the casing, a regulating weight adjustably mounted on said lower end portion, and a valve plate normally disposed within the limit of said casing and hingedly attached at its upper end to the corresponding end portion of said bar.

3. The combination of a pipe having an opening therein, a bar having an intermediate part hingedly connected to the bottom part of the pipe adjacent the opening, an adjustable weight on the lower part of the bar, said weight normally holding the bar across the opening with its upper end contacting an upper portion of the pipe, a valve member for closing the opening and having its top part hingedly connected to the upper part of the bar, a weight supported from the valve member for vertical movement, and means for holding the weight in adjusted position.

a casing attachable to a flue, a bar hingedly attached intermediate its ends to the bottom of said casing, the upper portion of said bar spanning the open outer end of said casing with its upper extremity engageable with the top wall of the casing to limit the swinging movement of the bar in one direction, the lower end portion of said bar depending below the casing, a regulating weight adjustably mounted on said lower end portion, and a valve plate normally disposed within the limit of said casing and hingedly attached at its upper end to the corresponding end portion of said bar, said valve plate corresponding in shape and proportion to the casing and being provided on its inner side with a guide fixture, and an adjusting weight slidable on said guide fixture.

3. The combination of a pipe having an opening therein, a bar having an intermediate part hingedly connected to the bottom part of the pipe adjacent the opening, an adjustable weight on the lower part of the bar, said weight normally holding the bar across the opening with its upper end contacting an upper portion of the pipe, a valve member for closing the opening and having its top part hingedly connected to the upper part of the bar, a weight supported from the valve member for vertical movement, and means for holding the weight in adjusted position.
